His Attorney.

UNITED STATES PATENT OFFICE

SVEND E. JOHANNESEN, OF PITTSFIELD, MASSACHUSETTS, ASSIGNOR TO GENERAL ELECTRIC COMPANY, A CORPORATION OF NEW YORK

ELECTRICAL WINDING

Application filed May 22, 1930. Serial No. 454,812.

My invention relates to electrical windings and has for its object the provision of an improved electrical winding and method of making it.

5 Although my invention has other applications, it is particularly useful in connection with electrical windings intended to be used in transformers and like electrical apparatus.

It has been found that for small and moderate capacity transformers intended for relatively high voltages, it is preferable to form the transformer with concentric primary and secondary windings. Insulation, usually in the form of cylinders, is positioned between 10 these windings so as to insulate the primary from the secondary voltage. It has also been found that it is desirable to use but one primary winding and likewise but one secondary winding for the transformer.

20 Some difficulty has been experienced when attempting to make high voltage windings, having the above mentioned desirable characteristics, with the methods of winding heretofore generally used because the high potential involved required a layer of major insulation so thick that a very broad path for "leakage flux" was created. This generally resulted in a very poor transformer regulation.

30 One arrangement was to form the windings with relatively long and shallow primary and secondary windings. In other words, the windings were formed with relatively long and narrow winding spaces. However, with 35 this arrangement it was very difficult to provide the necessary mechanical and electrical strength, particularly with those high potential windings wherein it was necessary to use a relatively small conductor wound into a

40 large number of turns per layer, such for example as one hundred or more. It will be appreciated that with such a large number of turns per layer, the maximum potential existing between successive layers may be very

45 great. Thus in the example given, the maximum potential between the layers may be the additive voltage of two hundred turns or more. Because of this very high potential difference existing between successive layers 50 a comparatively large amount of insulation

was required between them. Furthermore, it was generally necessary to increase the insulation to a value much in excess of that required between adjacent layers for safe operation because of the additive potential existing between a number of layers. Thus, in order to prevent a breakdown between those layers of the windings which are positioned a considerable distance apart it was necessary to provide a considerable amount of insulation at the end turns. This of course materially reduced the space factor, and besides tended to separate the adjacent layers to such an extent that the winding was weakened, at times to such an extent that it buckled and became distorted. Therefore, in order to provide the necessary electrical and mechanical strength it was frequently necessary to use a rather heavy and mechanically strong insulating cylinder between the windings.

55 In an effort to strengthen these windings mechanically so as to permit the use of a smaller insulating cylinder, it was proposed to form the high tension windings into single section disc-shaped coils, which in the assembled winding, would be placed side by side along the major insulating cylinder. Here again, however, relatively large voltage steps 60 were encountered, this time between adjacent coils rather than between adjacent layers.

70 Another arrangement was to wind the high tension windings into several back-turn sectional coils. While this arrangement tended to reduce the electrical stress throughout the winding, it left much to be desired in that the multiple section winding took up a great deal of space and moreover, it was found to be necessary often-times to reduce the insulation to such an extent in order to attain the required efficiency of operation that the 75 windings were not entirely satisfactory when considered in the light of the requirements for safe operation.

80 My invention in one of its aspects contemplates the provision of an electrical winding 85 of greater electrical and mechanical strength, one having a very large winding factor commensurate with the available winding space, and one which will operate at a comparatively high efficiency.

In carrying my invention into effect in one form thereof, I wind the turns of each layer of the winding so that they are positively interlocked mechanically between the turns of the adjacent layers on both sides. The turns of each layer are spaced so as to receive the turns of the adjacent layers between them in the spaces provided. The interlocking of the turns results in a very strong winding mechanically, and also effects a material increase in the electrical strength of the winding. This results from the fact that the number of turns per layer is greatly reduced by the spacing and consequently the maximum potential between adjacent layers also is greatly reduced. This reduction in the electrical stress in the winding, of course, effects a reduction in the amount of insulation required and thereby increases the winding factor materially.

I prefer to form the winding with substantially parallel convolutions, i. e., to form the layers by winding each turn along a circumference of the winding rather than in the form of a helix. In order to prevent the formation of a lop-sided winding, which would result if the cross-overs from one turn to the next of the turns of successive layers were in the same radial plane, I space the rows of cross-overs of succeeding layers at intervals so as to distribute the cross-over substantially uniformly through the winding, and moreover, so that no two of the rows will lie in the same radial plane.

For a more complete understanding of my invention reference should be had to the accompanying drawing in which Fig. 1 is a central longitudinal section of an electrical winding having horizontally wound layers formed in accordance with my invention; Fig. 2 is a plan view of an electrical winding similar to that shown in Fig. 1 but having many more turns per layer; Fig. 3 is a central longitudinal section of an electrical winding of modified form having horizontally wound layers formed in accordance with my invention; Fig. 4 is a central longitudinal section of an electrical winding having layers wound on a bias in accordance with my invention; and Fig. 5 is a central longitudinal section of an electrical winding having vertically wound layers formed in accordance with my invention.

Referring to the drawing, I have shown my invention in connection with electrical windings particularly useful in transformer applications. In Fig. 1 I have illustrated an electrical winding having horizontally wound layers. In forming this winding in accordance with my invention, I have spaced the turns of each layer so that they receive the turns of the adjacent layers in wedging, interlocking relation whereby the coil is strengthened both electrically and mechanically. As shown (Fig. 1), the electrical winding is

formed by winding a suitable electrical conductor 10 into a plurality of successive layers 11 on a suitable winding spool 12. The electrical conductor 10 is suitably insulated as by a coating of enamel or other suitable insulating material such as cotton. The spool 12 may be made of any suitable material but preferably is moulded from bakelite wood pulp sheets or some like composition. The winding surface 12a of the spool on which the turns of the first layer are wound may be roughened so as to assist in holding these turns in place when wound. Thus, a layer of sand paper 13 may be applied with its roughened abrasive surface outermost so as to engage and thus assist in holding in place against lateral movement the turns of the first layer of the winding. Such an arrangement for holding the turns of the first layer in place is described and claimed in the United States patent 85 granted to J. J. Vienneau, No. 1,550,189, dated August 18, 1925. While the winding surface 12a has been shown to be of cylindrical form it will be understood that it may have other suitable shapes. Thus, the spool may have a square or a polygonal cross-section.

The first layer is formed by winding a number of turns, for example six, 14, 14a, 14b, 14c, 14d and 14e spaced at intervals on the winding surface 12a from left to right; the second layer is formed by winding a like number of turns 14f-14k from right to left in the spaces formed between the turns of the first layer; the third layer is formed by winding turns 14l-14q in the spaces formed by the turns of the second layer, and so on each of the successive layers is formed by winding its turns in the spaces between the turns of the next preceding layer. The dashed lines in Fig. 1 indicate the center lines of the layers. It will be observed by reference to Fig. 1 that the turns 14, 14a-14e of the first layer are spaced at intervals along the length of the winding surface so that the distance between successive turns is equal to approximately .73 times the diameter of the conductor. This allows the turns of the second layer, and also of each succeeding layer to lie in comparatively wide spaces so as to be securely anchored between the turns of the preceding layer. It will be observed that when the spaces between adjacent turns equals .73 times the diameter of the conductor, the center lines of the layers are spaced apart a distance equal to one-half the diameter of the conductor. This insures a complete interlock between the wound turns.

Preferably, a spacer member 15 formed from some suitable material such as paper twine or an insulated conductor will be positioned between the successive turns of the first layer. As shown, this spacer member is proportioned so as to lie snugly against the adjacent turns of the first layer, and is shaped as the turns of the second layer are wound on so

as to conform with the curved lower portions of these turns. It is preferable to wind the spacer member at the same time as the conductor is being wound on to form the turns of the first layer. The spaces between the turns of the first layer, however, may be utilized by winding in them an electrical conductor parallel with the turns and permanently secured to the end turns of the layer in some suitable fashion as by soldering. Likewise, the spaces between the turns of the final layer may be utilized by winding in them an electrical conductor in parallel with the turns, the ends of this conductor also being permanently connected to the end turns of the layer in some suitable manner, as by soldering.

In order to make a more uniform and compact winding, I prefer to wind the turns along a circumference as shown in Fig. 2 rather than in the form of a helix. In other words, each turn will be wound so that its convolution lies in a plane at right angles to the longitudinal axis of the winding. At the end of each turn the conductor is shifted into the next succeeding turn and at the end of each layer, the shifting movement is reversed for the next layer. Thus, for each layer a longitudinally extending row of cross-overs 16 is formed. It will be understood that if the longitudinally extending cross-over rows of the succeeding layers occur substantially in the same radial location, i. e., each row builds up over the preceding row, a lop-sided winding would result. I prefer to distribute the cross-over rows 16 substantially uniformly by spacing them at substantially equal intervals (Fig. 2) about the winding so that no two of the rows will be in the same radial line. I am thus enabled to make a very uniform and symmetrical winding. One means for making my electrical winding automatically with the rows thus spaced is described and claimed in the copending application to L. C. Daniels, Serial No. 373,633, filed June 25, 1929.

It will be observed that by spacing the turns of each layer at intervals equal approximately to .73 times the diameter of the conductor, I reduce the voltage per layer to 58% of the voltage of a layer of the same width wound in the conventional manner, i. e., with the adjacent turns of each layer wound so as to contact with each other. More specifically, I have illustrated in Fig. 1 a winding with five layers of six turns each making a total of thirty turns. The maximum potential in the winding is the additive volts of twelve turns. It will be observed that this maximum potential occurs between the turns of alternate layers which are in contact. Thus, for example, the potential difference between the turn 14 of the first layer and the turn 14₁ of the third layer is the additive voltage of twelve turns. With the conventional method of winding, above referred to, the winding

would be formed with three layers of ten turns each, and the maximum potential between adjacent layers would be the additive volts of nineteen turns.

It is to be noted, however, that while my winding has five layers for a total of thirty turns to three layers of the conventional winding for the same total number of turns, my winding has a winding depth which may be either equal to or even less than the winding depth of the conventional winding. This is due to the fact that the turns wound in accordance with my invention are automatically wound much closer by reason of the wedging action between the spaced turns of each layer with those of the adjacent layers on both sides, and also in view of the fact that my winding requires much less insulation from layer to layer because the maximum potential between the layers is greatly reduced. Layer insulation heretofore generally used is usually unnecessary in my winding. In other words, I have provided a very large winding factor commensurate with the available winding space. This elimination of layer insulation also effects an increase in the efficiency of operation of the winding. Furthermore, the elimination of layer insulation increases greatly the speed of automatic winding. It will be understood that if it be necessary for the operator to insert layer insulation very little time is saved by automatic winding.

Another important feature of my invention is the increased mechanical strength of the winding. It will be observed that each turn of my winding is wedged between the turns of the adjacent layers. It also will be observed that when the turns are spaced at intervals equal to approximately .73 of the diameter of the conductor the center lines of each layer are practically coincident with the tangents common to the adjacent portions of the turns of the adjacent layers on both sides. Thus, the turns are securely anchored in place and are forced to retain the positions they have assumed when wound. Obviously, this feature is very important when the windings are being formed on automatic machines.

I have illustrated in Fig. 3 a winding of modified form having layers wound horizontally in accordance with my invention. Each layer 21 of this winding, like each layer 11 of Fig. 1, is formed by winding a number of turns 22, 22_a, etc., spaced at intervals along the length of the winding surface. It will be observed, however, by reference to Fig. 3 that the spaces between the turns in each layer are slightly less than .73 of the diameter of the conductor. The advantage of this arrangement is that the alternate layers do not touch as is the case in Fig. 1 and consequently the maximum potential in the modified winding is slightly less than that in the winding of Fig. 1. Thus in the modified winding, the potential be-

tween adjacent layers rises from a minimum to a maximum, this maximum being the maximum potential occurring in the winding. In other words, the maximum potential occurring in this winding occurs between the turns 22 and 22_k rather than between the turns 22 and 22_l, as would be the case if the turns of the alternate layers touched.

Otherwise, this winding of modified form 10 is substantially the same as that shown in Fig. 1. It is provided with a winding spool 23 which may have a roughened winding surface 23a. The spacing member 24 is positioned between the spaced turns of the 15 first layer and is shaped by the turns of the first and second layers as they are wound on so as to conform with the curved surfaces of the adjacent turns of the first layer and the bottom curved portions of the turns of the 20 second layer. The turns of this winding may also be and preferably are wound along a circumference of the winding as are the turns of the windings shown in Figs. 1 and 2. If desired, the spaces between the turns 25 of the first and last layers may be utilized by winding in the electrical conductors parallel with the turns of these layers and connected with their end turns.

The electrical windings thus far described, 30 i. e., those windings wherein the layers are wound horizontally, are adapted particularly for moderate voltages such as 13,000 or less.

For higher voltages, such for example as 35 those ranging between 13,000 and 66,000, I prefer to wind the layers on a bias as shown in Fig. 4, rather than horizontally as shown in Figs. 1 and 3. Referring to Fig. 4, I have shown an electrical conductor 30 wound in 40 bias layers 31 on a suitable winding spool 32. The winding spool may be provided with a roughened winding surface 32a so as to assist in holding the turns of the first layer in place against lateral movement. 45 Preferably, the layers will be wound on a bias substantially 30° from the horizontal. One arrangement of winding these layers is as follows: The first turn 33, which forms the first layer, is wound on the winding surface 50 in spaced relation with the inner surface of the left hand spool head. The second turn 33a is wound beside it on the winding surface; however, instead of continuing on the winding surface, the third turn 33b 55 is laid in the space between the first turn 33 and the spool head. The second layer is thus formed by the turns 33a and 33b. It will be observed that the first turn 33 will have been spaced such a distance from the left hand 60 spool head that the center line of the second layer will be on a bias substantially 30° from the horizontal, as is indicated on the drawing.

The fourth turn 33c, i. e., the first turn of 65 the third layer, is laid in the space formed

between the turns 33a and 33b of the second layer; the next turn 33d is wound on the winding surface beside the turn 33a, thereby completing the third layer. The sixth turn 33e of the winding is wound on the winding surface beside the fifth turn 33d, while the seventh turn 33f is laid in the space between the turns 33c and 33d of the third layer. The last turn 33g of the fourth layer is laid in the gutter between the turns 33b and 33c. 70 It will be observed that four layers have been formed on a bias substantially at 30° with the horizontal. The fifth, sixth, and each of the remaining layers of the winding will be wound with their turns laid in the 80 spaces between the turns of the next preceding layer.

It will be observed that each turn wound on is securely anchored in a space provided between turns of the previously wound layer. 85 Therefore, my method of winding bias layers lends itself readily to automatic winding. This is an important advantage over the conventional method of winding bias layers, i. e., the method wherein the adjacent turns 90 of each layer are wound so as to contact with each other. It will be understood that with the conventional method, it has been extremely difficult to hold the wound turns in place.

It will be observed that the spaces provided between the turns of each layer are equal approximately to .73 of the diameter of the conductor being wound so that the center line of each of the bias layers is substantially coincident with the tangents common to the adjacent portions of the turns of the layers on both sides. It is to be understood, however, that these spaces may be less than .73 of the diameter of the conductor so that the alternate layers rather than touching as shown in Fig. 4 will be spaced in the manner of the turns of Fig. 3. It is also to be understood that the turns of the bias winding preferably will be wound so that their convolutions lie in planes perpendicular to 100 the axis of the winding. If desired suitable conductors may be wound in the spaces between the turns of the first and last layers in 105 parallel with these turns and permanently connected in any suitable manner with the 110 end turns.

For still higher voltages, it is preferable to wind the layers vertically as shown in Fig. 5. The winding spool 40 in this case is provided with a winding surface 40a, preferably 120 roughened, on the inner surface of one of the spool heads, as for instance the left hand head as viewed in Fig. 5. As shown, the turns 41, 41a and 41b of the first layer are wound vertically on the roughened winding surface and are spaced so as to receive the turns 41c and 41d of the second layer between them. If desired, a suitable spacer 42 similar to those shown in Figs. 1 and 3 may be provided between the turns 41, 41a and 41b of the 125 130

first layer. The turns of the third layer are wound in the spaces provided by the turns of the second layer, and the turns of each of the remaining layers of the winding likewise 5 are wound in the spaces provided by the turns of the next preceding layer. It will be observed that the spaces between the turns of each layer are approximately .73 of the diameter of the conductor being wound so that 10 here again the center line of each layer is substantially coincident with the tangents common to the adjacent portions of the turns of the layers on both sides. It is to be understood, however, that the spacing between the 15 turns may be less so that the turns of the alternate layers will be spaced, as are the turns of the winding shown in Fig. 3, whereby the potential between the layers of the winding is reduced. Preferably, the turns of this winding also will be wound with their convolutions lying in planes perpendicular to the axis of the winding. Here again, the spaces between the turns of the first and last layers 20 may be utilized by winding in them conductors parallel with the turns and connected 25 permanently with the end turns.

It is to be noted that I am enabled by my method of winding to provide relatively long and shallow electrical windings which are 30 sufficiently strong mechanically to sustain themselves without the application of relatively large amounts of insulation; the mechanical interlock between the turns provides a very strong winding, while the reduction 35 in voltage from layer to layer effected by the spacing of the turns necessitates the use of but a relatively small amount of insulation. It also is to be noted that all of the windings whether they be of the horizontal, vertical or 40 bias type lend themselves readily to automatic winding as well as to winding by hand.

While I have shown several embodiments 45 of my invention, it will be understood, of course, that I do not wish to be limited thereto since many modifications may be made and I, therefore, contemplate by the appended claims to cover any such modifications as fall 50 within the true spirit and scope of my invention.

55 What I claim as new and desire to secure by Letters Patent of the United States, is:

1. An electrical winding comprising an electrical conductor wound into a plurality of layers, the turns of each layer of said conductor being spaced apart, the spaces between said turns being equal to a substantial portion of the diameter of said conductor so as to receive the turns of the adjacent layers between them in interlocking relation.

60 2. An electrical winding comprising an electrical conductor wound into a plurality of successive layers, the turns of each layer being spaced apart a distance equal to a substantial portion of the diameter of said conductor but not greater than .73 times the di-

ameter of the conductor whereby they receive the turns of the adjacent layers between them.

3. An electrical winding comprising an insulated electrical conductor wound into a plurality of successive layers, the turns of each layer being spaced apart a distance at least as great as the radius of said insulated conductor but not greater than .73 times the diameter of said insulated conductor so as to receive the turns of the adjacent layers between them in mechanical interlocking relation. 70 75

4. An electrical winding comprising an insulated electrical conductor wound into a plurality of layers, the turns of each layer being spaced to receive the turns of the adjacent layers on both sides between them so that the center line of each layer is substantially coincident with the tangents common to the adjacent portions of the turns of the adjacent layers. 80 85

5. An electrical winding comprising an electrical conductor wound into a plurality of successive layers, the turns of each layer being spaced apart a distance substantially equal to .73 times the diameter of the conductor. 90

6. An electrical winding comprising an insulated electrical conductor wound into a plurality of successive layers, the turns of each layer of said insulated conductor being wound on a circumference and being spaced apart a substantial distance so as to receive the turns of the adjacent layers between them in mechanical interlocking relation. 95 100

7. An electrical winding comprising an electrical conductor wound into a plurality of successive layers, the turns of each layer being spaced apart at substantially regular intervals and wedged into interlocking relation with the spaced turns of the adjacent layers on both sides of it, the spacing of said turns being equal to a distance at least as great as the radius of said conductor but not greater than .73 times the diameter of the conductor whereby the turns of said adjacent layers are in close proximity. 105 110

8. An electrical winding comprising an electrical conductor wound into a plurality of layers, the turns of each layer being wound on a circumference so that their convolutions lie in planes at right angles to the longitudinal axis of the winding and parallel to each other, said turns also being spaced to receive the turns of the adjacent layers on both sides between them so that the center line of each layer is substantially coincident with the tangents common to the adjacent portions of the turns of the adjacent layers. 115 120 125

9. The method of winding an electrical conductor to form a coil having superposed layers which consists in winding said conductor into a layer with the successive turns of each layer spaced apart a distance equal 130

to a substantial portion of the diameter of the conductor, then winding a second layer of turns within the spaces between the turns of said first layer and so on winding each successive layer of turns in the spaces between the turns of the preceding layer until the desired number of layers have been wound.

10. The method of winding an electrical conductor into a coil having superposed layers which consists in winding said conductor into a layer with the successive turns thereof spaced apart a distance greater than the radius of said conductor but not greater than .73 times the diameter of the conductor,
15. winding a second layer of turns within the spaces between the turns of said first layer and so on winding each successive layer of turns in the spaces between the turns of the preceding layer until the desired number of 20 layers have been wound.

11. The method of winding an electrical conductor to form a coil with superposed layers which consists in winding said conductor on a winding form with the turns 25 wound on the circumferences of said form and spaced apart at regular intervals, the length of the intervals being substantially equal to .73 times the diameter of the conductor, then winding said conductor in the 30 spaces between the turns of the wound layer so as to form a second layer and so on winding each successive layer of turns in the spaces between the turns of the preceding layer until the desired number of layers have 35 been wound.

12. In the winding of coils wherein the turns are wound on a circumference, the method of distributing the cross-overs which consists in bringing the cross-overs of successive layers at different radial portions of the winding.

13. In the winding of coils wherein the turns are wound on a circumference, the method of distributing the cross-overs which 45 consists in crossing over from one turn to the next of each layer so as to form rows of cross-overs extending lengthwise of the winding, and spacing the cross-over rows of successive layers at intervals so as to bring them to different radial portions of the winding.

14. In the winding of coils wherein the turns are wound on a circumference, the method of distributing the cross-overs which 55 consists in crossing over from one turn to the next of each layer in the same radial plane so as to form cross-over rows extending lengthwise of the winding and substantially parallel with its axis, and spacing the cross-over rows of successive layers at substantially 60 regular intervals so as to bring them to different radial portions of the winding.

15. An electrical winding comprising an electrical conductor wound into a plurality 65 of layers, the turns of each layer being wound substantially along a circumference of the

winding so that their convolutions lie in parallel planes positioned substantially at right angles to the longitudinal axis of the winding, the cross-overs from one turn to the next in each layer forming a longitudinally extending row and the cross-over rows of successive layers being spaced at intervals so as to lie in different radial positions in the winding.

16. An electrical winding comprising an 75 electrical conductor wound into a plurality of layers, the turns of each layer being spaced apart, the spaces between said turns being at least as great as the radius of said conductor but not greater than .73 times the 80 diameter of the conductor, said turns also being wound substantially along a circumference of the winding so that their convolutions lie in parallel planes positioned substantially at right angles to the longitudinal 85 axis of the winding, the cross-overs from one turn to the next in each layer forming a row extending lengthwise of the winding and substantially parallel with its axis, and the cross-over rows of succeeding layers being 90 spaced at substantially regular intervals so as to bring them to different radial portions of the winding.

17. An electrical winding comprising an 95 electrical conductor wound into a plurality of layers, the turns of each layer being spaced at substantially regular intervals, the lengths of said intervals being greater than the radius of said conductor but not greater than .73 times the diameter of the conductor whereby 100 said turns are wedged into interlocking relation with the spaced turns of the adjacent layers on both sides of it, the turns of each layer also being wound substantially along a circumference of the winding so that their convolutions lie in parallel planes positioned substantially at right angles to the longitudinal axis of the winding, the cross-overs from one turn to the next in each layer forming a longitudinally extending row and the 110 cross-over rows of successive layers being spaced at intervals so as to lie in different radial positions in the winding.

In witness whereof, I have hereunto set 115 my hand this 20th day of May, 1930.

SVEND E. JOHANNESEN.
